(57) **CLAIM**

We claim the ornamental design for a carburetor, as shown and described.

DESCRIPTION

FIG. 1 is a front view of a carburetor, showing the claimed design.

FIG. 2 is a rear view of the carburetor of FIG. 1.

FIG. 3 is a first side view of the carburetor of FIG. 1.

FIG. 4 is a second side view of the carburetor of FIG. 1.

FIG. 5 is a top plan view of the carburetor of FIG. 1.

FIG. 6 is a first perspective view of the carburetor of FIG. 1; and,

FIG. 7 is a second perspective view of the carburetor of FIG. 1.

The broken lines used in the figures are for illustrative purposes only and form no part of the claimed design.
